AUTOMATIC GAS CUT-OFF.

1,050,646.

Specification of Letters Patent. Patented Jan. 14, 1913.

Application filed April 6, 1912. Serial No. 688,923.

To all whom it may concern:

Be it known that I, MARTIN LUTHER GROVE, a citizen of the United States, and a resident of Tylersburg, in the county of 5 Clarion and State of Pennsylvania, have made certain new and useful Improvements in Automatic Gas Cut-Offs, of which the following is a specification.

My invention relates to improvements in 10 automatic gas cut-offs, and it consists in the combinations, constructions and arrangements herein described and claimed.

The object of the present invention is to provide a simple, efficient and comparatively 15 inexpensive automatic gas cutoff having an inlet and an outlet and provided with means operable through an abnormal decrease in the flow of the gas for closing the outlet, and equipped with separate means for producing 20 a sub-normal flow within the cutoff to cause an operation of the said means when there is an abnormal increase in the flow of gas through the inlet.

A further object of the invention is to 25 provide an automatic gas cutoff of this character in which the automatically operable mechanism will be located wholly within the casing, and which will be equipped with exteriorly operable gas tight means for re- 30 setting the cutoff and for adjusting the said means for producing a sub-normal flow in the cutoff when there is an abnormal increase in the flow of gas through the inlet.

A further object of my invention is to 35 provide means exterior to the gas chamber for resetting the cut-off valve within the chamber so as to permit the free flow of gas.

A further object of my invention is to provide a simple device having few parts and 40 therefore not liable to get out of order, which will positively cut off the flow under the conditions stated.

My invention is illustrated in the accompanying drawing forming part of this application, in which—

Figure 1 is a vertical section through the device, Fig. 2 is a horizontal section along the line 2—2 of Fig. 1, and Fig. 3 is a plan view of a drop arm and adjustable closure 50 carried thereby.

In carrying out my invention I provide an oblong casing 1 which is preferably made of cast metal, such as brass. At one end of

the casing toward the bottom thereof is a threaded opening 1^x to receive a pipe 2 55 which is the inlet pipe. At the opposite end of the casing is a similar threaded opening 1^y for the outlet pipe 3. Within the casing is a partition 4 dividing the interior of the casing into inlet and outlet compartments 60 A and B, these compartments communicating with each other by means of an opening 4^x at the bottom of the partition 4. In one corner of the compartment B is a compartment C constituting an outlet passage and 65 formed by a partition 5 of the shape shown in Fig. 1. The compartment B is adapted to communicate with the compartment C through an opening 5^x in the partition 5.

The casing 1 is provided with a cover 6 70 which may be fastened to the casing by means of bolts 7, suitable packing 8 being provided to make the joint tight. The cover bears two hand wheels 9 and 10. The former has a stem 9^x which is threaded to 75 engage the threaded lug 11, so that as the hand wheel 9 is turned the stem 9^x will move into or out of the compartment A. The hand wheel 10 likewise has its stem 10^x threaded into the lug 12 so that the stem 80 may be moved upwardly or downwardly as the wheel 10 is turned. The lower part of the stem is provided with a head 13. Within the compartment A is a closure 14 arranged to close one end of the opening or 85 passage 4^x, this closure being provided with a resilient gasket 15 arranged to bear on the ends of the walls of the passage 4^x. The closure is carried at the lower end of a bell crank lever 16 which is pivoted at 17 90 in the side walls and whose short arm 18 is normally pressed upon by a spring 19. The upper end of the spring is engaged by a lever 20 pivoted at 21 and provided at its opposite end with a yoke 21^x arranged to 95 straddle the stem 9^x so that when the hand wheel 9 is turned the lever 20 may be moved so as to exert greater or less force on the spring 19. In the compartment B is an arm 22 constituting a tripping device and having 100 at its lower end a plunger 23 arranged to enter the opposite end of the passage 4^x from the closure 14. The upper end of the arm 22 is pivoted at 24 and is provided with an integral hook or bent over portion 24^a. 105 At 25 is pivoted an L-shaped arm 26 having

a shoulder 26^a at its end, and being provided with a slot 27 arranged to receive the threaded reduced portion 28 of a closure 29 similar to the closure 14, a milled nut 30 securing the closure to the arm.

From the foregoing description of the various parts of the device the operation thereof may be readily understood. The gas enters at the inlet 2 and impurities in the 10 gas are screened out by means of the screen 31 which, as will be seen from the drawing, is held by flanges 32 projecting from the side walls. If the flow of the gas is normal then the closure 14 will be open and the gas 15 will pass from the compartment A into the compartment B pushing back the plunger so as to bring the arm 22 into the full line position shown in Fig. 1. While in this position a pin 22^x carried by the arm 22 engages one end of a setting lever 32, the 20 opposite end of the lever 32 being engaged by the shoulder 26^a of the arm 26. The gas passes through the compartment B in the manner indicated by the arrows, through 25 the opening 5^x and out through the exit pipe 3. Now if for any reason the flow of the gas should decrease below the safety limit, which may be predetermined, the gas 30 will not have force enough to push the plunger 23 out of the passage 4^x, so that the arm 22 will move into the dotted line position shown in Fig. 1 by gravity. The movement of the arm 22 will withdraw the pin 22^x from the end of the lever 32 and will at 35 the same time bring the hooked extension 24^a on the upper end of the lever, thereby forcing the opposite end upwardly and tripping the arm 26, which will fall immediately into the dotted line position, the closure 29 entering the opening 5^x to prevent a 40 further flow of gas. It will thus be seen that the gas will be cut off automatically by the abnormal reduction of the flow. On the other hand with the apparatus set as 45 shown in Fig. 1, let us assume that the flow increases beyond a predetermined safety limit. Then the closure 14 will be forced into the end of the passage 4^x by the increased flow thus cutting off the flow of gas 50 into the chamber B. As soon as the flow in the chamber B lowers, the arm 22 will swing to the dotted line position, since no gas is coming to keep it in the full line position. This will trip the arm 26 in the manner 55 already described, thereby effecting the closure of the opening 5^x. It will thus be seen that the increase in the flow of the gas really causes the operation of the low pressure closure.

60 The wheel 9, is for the purpose of regulating the point at which the closure 14 will act, since by moving the wheel more or less tension is put on the spring 19, and hence more or less gas pressure will be required 65 to force the closure against the end of the

passage 4^x. The wheel 10^x is for the purpose of resetting the device, *i. e.*, opening the closure 29. When the wheel is screwed down the head 13 will move to the dotted line position, thereby raising the arm 26 so as to allow the shoulder 26^a to drop behind the end of the lever 32. If the flow of the gas has become normal the movement of the arm 22 will cause the lever 32 to hold the arm 26. Any increase or decrease of flow beyond the predetermined limits will result in the automatic cut-off of the gas as described. If the head 13 is left in the dotted line position shown in Fig. 1, then of course the arm 26 will be prevented from falling. In order to insure the closing of the opening 5^x I may make the closure 29 adjustable along the arm 26 by the tightening or loosening of the nut 30.

The device is simple, has few parts, and is not liable to get easily out of order. It may be accurately adjusted to work at predetermined pressures.

I claim:—

1. A casing provided with an inlet and an outlet, a partition within said casing provided with an opening, an arm pivoted on each side of said partition, one of said arms being provided with a closure for said opening, the other arm being provided with a plunger arranged to register with said opening, a second partition provided with an opening, means for closing the opening in said second partition, and a pivoted trip member arranged to be engaged by the pivoted arm bearing the plunger for operating the closure for the opening in said second partition.

2. A casing provided with an inlet and an outlet, a partition within said casing provided with an opening, an arm pivoted on each side of said partition, one of said arms being provided with a closure for said opening, the other arm being provided with a plunger arranged to register with said opening, a second partition provided with an opening, a weighted arm pivotally disposed near said second partition and being provided with a closure arranged to enter the opening in said second partition, a pivoted trip member arranged to engage one end of said weighted arm and to be engaged by the pivoted arm bearing the plunger.

3. A casing provided with an inlet and an outlet, a partition within said casing provided with an opening, an arm pivoted on each side of said partition, one of said arms being provided with a plunger arranged to register with said opening, a second partition provided with an opening, a weighted arm pivotally disposed near said second partition and being provided with a closure arranged to enter the opening in said second partition, a pivoted trip member arranged to engage one end of said weighted arm.

arm and to be engaged by the pivoted arm bearing the plunger, and means for adjusting the distance of the first named closure from the first named opening.

5. A casing provided with an inlet and an outlet, a vertical partition within said casing provided with an opening, an arm pivoted on each side of said partition, one of said arms being provided with a closure for said opening, the other arm being provided with a plunger arranged to register with said opening, a second partition provided with an opening, a weighted arm pivotally disposed near said second partition and being provided with a closure arranged to enter the opening in said partition, a pivoted trip member arranged to engage one end of said weighted arm and to be engaged by the pivoted arm bearing the plunger, the movement of the latter arm serving to release the weighted arm through the medium of the pivoted trip.

5. A casing provided with an inlet and an outlet, a vertical partition within said casing provided with an opening, an arm pivoted on each side of said partition, one of said arms being provided with a closure for said opening, the other arm being provided with a plunger arranged to register with said opening, a second partition provided with an opening, a weighted arm pivotally disposed near said second partition and being provided with a closure arranged to enter the opening in said partition, a pivoted trip member arranged to engage one end of said weighted arm and to be engaged by the pivoted arm bearing the plunger, the movement of the latter arm serving to release the weighted arm through the medium of the pivoted trip, and means including a spring for adjusting the distance of the first named closure from the first named opening.

6. A casing provided with an inlet and an outlet, a vertical partition within said casing provided with an opening, an arm pivoted on each side of said partition, one of said arms being provided with a closure for said opening, the other arm being provided with a plunger arranged to register with said opening, a second partition provided with an opening, a weighted arm pivotally disposed near said second partition and being provided with a closure arranged to enter the opening in said partition, a pivoted trip member arranged to engage one end of said weighted arm and to be engaged by the pivoted arm bearing the plunger, the movement of the latter arm serving to release the weighted arm through the medium of the pivoted trip, means including a spring for adjusting the distance of the first named closure from the first named opening, and means exterior of the casing for resetting said weighted arm.

65. 7. An automatic gas cutoff including a

casing having an inlet and an outlet, means operable through an abnormal decrease in the flow for closing the outlet, and separate means for producing a sub-normal flow within the cutoff to cause an operation of the first-mentioned means when there is an abnormal increase in the flow through the inlet.

8. An automatic gas cutoff including a casing having communicating inlet and outlet compartments and provided at the inlet compartment with an inlet and having an outlet at the outlet compartment, means located in the outlet compartment and operable through an abnormal decrease in the flow of the gas for closing the said outlet, and separate means operating in the inlet compartment for producing a sub-normal flow within the outlet compartment when there is an abnormal increase in the flow of the gas into the inlet compartment.

9. An automatic gas cutoff including a casing having an inlet and an outlet, a closure movable toward and from the outlet, means for holding the closure in its open position, and tripping mechanism operable through an abnormal decrease in the flow of the gas for releasing the closure to permit the same to close the outlet, and separate means for producing a sub-normal flow within the cutoff to cause an operation in the tripping mechanism when there is an abnormal increase of the flow of the gas through the inlet.

10. An automatic gas cutoff comprising a casing having an inlet and an outlet, a closure movable toward and from the outlet, setting mechanism for holding the closure in its open position, said mechanism including means operable through an abnormal decrease in the flow of the gas for releasing the closure to permit the same to close the outlet, and separate means for producing a sub-normal flow within the cutoff to cause an operation of the said mechanism when there is an abnormal increase in the flow of the gas through the inlet.

11. An automatic gas cutoff comprising a casing having an inlet and an outlet, means located wholly within the casing and operable through an abnormal decrease in the flow for closing the outlet, said means including a pivoted closure, and mechanism for setting and tripping the same, means operable exteriorly of the casing for swinging the closure to its open position to reset the same, and separate means for producing a sub-normal flow in the cutoff to cause an operation of the first-mentioned means when there is an abnormal increase in the flow through the inlet.

12. An automatic gas cutoff comprising a casing having an inlet and an outlet, means operable through an abnormal decrease in the flow for closing the outlet, and separate

means for producing a sub-normal flow in
the cutoff to cause an operation of the first-
mentioned means when there is an abnormal
increase in the flow through the inlet, said
5 separate means including a pivoted closure,
a spring yieldably maintaining the closure
in an open position, and exteriorly operable

means connected with the spring for adjust-
ing the said closure.
